UNITED STATES PATENT OFFICE.

JAMES H. BURGHER, OF RUSSELLVILLE, KENTUCKY.

TOY CANNON.

1,260,633.

Specification of Letters Patent. Patented Mar. 26, 1918.

Application filed September 7, 1917. Serial No. 190,215.

To all whom it may concern:

Be it known that I, JAMES H. BURGHER, a citizen of the United States, residing at Russellville, in the county of Logan and 5 State of Kentucky, have invented certain new and useful Improvements in Toy Cannons, of which the following is a specification.

This invention relates to toys, and it relates more particularly to toy guns or cannons.

One of the objects of this invention is to provide an improved form of rapid firing gun or cannon of the magazine type.

15 Another object is to provide a device of this character which may be manipulated with ease by a child or other person who is inexperienced and inexpert in the manipulation of machinery generally.

20 Another object of this invention is to provide a device of this character which is so simple of construction that it may be manufactured and vended at the minimum cost.

Another object is to provide a device of 25 this character which is strong and durable, and which will not easily get out of repair.

Other objects and advantages may become apparent to persons who read the following detailed description in connection 30 with the accompanying drawings in which,—

Figure 1 is a side elevation view, the front portion being shown in vertical section, certain elements of the rear portion being shown in dotted lines.

35 Fig. 2 is a horizontal sectional view, and—

Fig. 3 is a transverse vertical sectional view on the line 3—3 of Fig. 1.

In these drawings, in which similar reference characters correspond to similar parts throughout the several views, the barrel of 40 the cannon preferably consists of a rear section 10, a front section 11 and a middle section 11^a the sections 11^a and 11 being united at 12 and secured by any appropriate means, while the sections 11^a and 10 are united at 45 12^a. The barrel may be formed of wood, metal, or other material according to the requirements or desire of the manufacturer.

50 The barrel is mounted upon an axle 13, the latter being mounted upon wheels 14.

Brace rods 15 extend from the axle to the rear end of the front section 11 and are secured thereto by suitable means such as shown in 16. A limber 17 has its front end 55 portion secured to the axle 13 and to brackets 18, the latter consisting of a pair of hangers 19, hangers 20 and connecting bars 21. The brackets have their upper ends secured respectively to the opposite sides of the barrel 60 section 10, and depend to a considerable distance below the lower side of said barrel section. The barrel section 11^a is provided with a concentric bore 22, and the section 10 is provided with a cavity 23, so that the 65 section 10 constitutes a housing which communicates with the bore 22, which latter communicates with a concentric bore 24 which extends entirely throughout the length of the section 11. The section 11 is provided with an eccentric bore 25 which constitutes a magazine in which the balls or missiles 26 are stored preparatory to shooting the same through the section 11. Of course, the balls being round, the bores 24 70 and 25 are circular in cross section, or cylindrical, and I provide a circular inlet opening 27 which is normally closed by a plug 28, the latter being provided with a sight 29 which is formed thereon, and which also 75 serves as a handle whereby the plug 28 may be removed. A partition 30 separates the bores 24 and 25, and this partition is provided with an aperture 31 at its rear end. A plunger 32 is mounted for longitudinal 80 movement through the bore 22, this plunger being provided with a head 33 which is of a diameter greater than that of the bore 22, so that it serves as a stop, while the rear end of the section 11^a serves as a stop which 85 coöperates with the stop 33 for limiting forward movement of the plunger 32. The head 33 is provided with a rearward extension or apertured lug 34. A hooked member 35 has its front end connected to lug 34 by a pivot 90 36. The free end of the link of hook member 35 is provided with a shoulder 37 and with a rearward extension 38. The member 35 is also provided with a depending hump or guide element 39. The function of the link 100 35 will presently appear.

The section 11^a is provided with a pair of

- eccentric chambers or bores 40 in which are seated a pair of retractile springs 41 which have their front ends secured to the section 11^a and extend rearwardly and have their 5 rear ends secured to the head 33. Therefore, these springs are operable to draw the plunger 32 forward instantaneously so as to shoot the balls 26 one by one from the muzzle of the cannon.
- 10 The operating mechanism consists of a wheel or rotary member 42 which is supported on an axle 43, the latter being supported by the hangers 19 and being rotatable therein. The rotary member 42 is 15 provided with a beveled gear wheel 43^a which is fixed with relation to the member 42, and is rotatable by means of a beveled pinion 44, the latter being supported by and rotatable by means of a crank shaft 45 20 which is provided with a handle 46 and is journaled in the handle 20.

The rotary member 42 is provided with diametrically opposed teeth or projections 47.

- The operation of the device is as follows:
- 25 When it is desired to load the magazine, the combined sight and handle 29 is grasped, and the plug 28 is thereby removed, whereupon the balls 26 may be dropped through the aperture 27 until the magazine is filled, 30 and then the plug 28 is replaced and the sight 29 is properly adjusted. In thus filling the magazine, the balls naturally roll rearward of the barrel, because the front end of the cannon is higher than its rear 35 end, so that the partition 30 is rearwardly inclined. The plunger 32 is normally in its forward position, so that the rearmost ball 26 is prevented from dropping through the aperture 31. Now, it being desirable to 40 shoot, the handle 46 is turned, thereby turning the wheel or pinion 44, the wheel 43^a, and the rotary member or preparatory actuator 42, so as to bring one of the teeth 47 into engagement with the shoulder 37, for 45 drawing the latter rearward and thereby drawing the plunger 32 into its rearmost position as shown in the drawings. When the plunger 32 and the link 35 have reached their rearmost position, the shoulder 38 is 50 arrested, in its downward movement, by means of a stop 48, while the contiguous tooth 47 continues its downward movement until it is disengaged from the shoulder 37, whereupon, the plunger 32 and the link 35 55 are free to be drawn quickly forward by means of the springs 41. However, one of the balls 26 will have dropped through the opening 31, in front of the plunger 32, so that the latter drives this ball with considerable velocity through the bore 24. In 60 order to prevent the link 35 from dropping too low, the depending element 35 co-operates with the cylindrical surface of the member 42 and with the bottom of the housing

10, the element 39 thus supporting the free 65 end of the link 35 while each tooth 47 moves into engagement with the shoulder 37.

From the foregoing, it will be seen that I have provided a device of this character which is thoroughly sane and practical as 70 a toy and as a means of education along military lines.

Although I have described this device minutely, it is to be understood that my invention is not limited to these exact details 75 of construction and arrangement of parts, but my invention is susceptible of change within the scope of the appended claims.

What I claim as my invention is:

1. A magazine gun comprising a barrel 80 having a longitudinal bore through which the missiles are discharged, said barrel also having a magazine and having a partition between said magazine and said longitudinal bore, said partition being provided with an 85 aperture through which the missiles pass from the magazine to said longitudinal bore said barrel being also provided with a sight and with an opening in which said sight is normally fitted, said sight being removable 90 from said opening for allowing the missiles to be placed in said magazine.

2. A gun comprising a bore through which the missiles are discharged, a magazine communicating with said bore and operable to feed the missiles by gravity into said bore, a plunger, means for moving said plunger forward in said bore, so as to discharge the respective missiles and to prevent the immediate feeding of other of said 100 missiles while the discharge is taking place, a hooked member having one end pivotally connected with said plunger and having its hook extending downward, a gear wheel supported under said hooked member and provided with radial extensions, a gear wheel meshing with the first said gear wheel, a shaft carrying the second said gear wheel and extending rearwardly therefrom, and a handle for rotating said shaft and thereby 105 rotating said wheels so as to carry said radial extensions into engagement with said hook and to move the latter rearwardly.

3. A toy cannon comprising primarily 110 separate front and rear and intermediate barrel sections normally united by appropriate means, the front section comprising a discharge bore and a magazine which extend approximately throughout the length of said front section which latter also has an 115 opening through which missiles may pass from said magazine into said discharge bore, said intermediate section being formed with a bore which is aligned with said discharge bore, said intermediate section being also formed with recesses at opposite sides of its bore, rear section comprising a housing 120 which communicates with said recesses, a

plunger slideable through the bore of said intermediate section, an actuator extending into said housing, means for operatively connecting said actuator with said plunger 5 for moving the latter rearward, and springs each having one end extending into one of said recesses and secured to said intermediate section and having its other end secured to said plunger, whereby the said plunger

is caused to discharge the missiles after being moved rearward by said actuator.

In testimony whereof I affix my signature in presence of two witnesses.

JAMES H. BURGHER.
